BACON TRAY

Reynolds Guyer, St. Paul, Minn., assignor to Waldorf Paper Products Company, St. Paul, Minn., a corporation of Minnesota

Application October 15, 1951, Serial No. 251,284

2 Claims. (Cl. 229—87)

This invention relates to an improvement in bacon tray and deals particularly with a package suitable for use in packing strips of bacon or a similar product.

In recent years, the use of paperboard packages to contain strips of bacon and similar meats has become increasingly popular. The packages may be of numerous types. One common type of package comprises a back board having marginal flanges connected thereto. The strips of bacon are placed upon the back board and the flanges are folded over the ends of the bacon strip as well as over the first strip of the series. The tray thus formed is wrapped with cellophane or some other transparent wrapping which permits the customer to view the contents.

This type of package has certain disadvantages. In the first place the marginal flanges must fold closely about the bacon, thus producing a package of varying thickness which is difficult to overwrap neatly. In the second place the paperboard directly contacts the bacon and creates a likelihood of stain due to a wicking action of the paperboard. Finally the package requires considerable hand manipulation in most instances to fold the marginal flanges and to lock them in place until the package may be wrapped. As the package must be sold in competition, the package must be inexpensively constructed.

A feature of the present invention resides in the provision of a bacon tray in which the package is lined with cellophane or a suitable transparent material. As a result the wrapper forms a part of the original package and the resulting package need not be overwrapped. A further feature of the present invention resides in the fact that the transparent liner is interposed between the bacon and the body of the package, thereby preventing any stain in the paperboard due to contact with the greasy contents.

A further feature of the present invention resides in the low cost with which the package may be constructed. The package acts to enclose one marginal edge of each strip of bacon and also to cover the whole strip at one edge of the package, leaving only the stepped strip edges in view.

A further feature of the present invention resides in providing a wrapper which is of considerable dimensions, but which uses an extremely small amount of paperboard. In view of the fact that one blank dovetails with another, two blanks may be cut from a rectangular sheet with virtually no waste of paperboard.

A further feature of the present invention resides in the provision of a package which may be easily and quickly assembled. The package lends itself very well to a continually movable assembly operation in which the package is folded either manually, automatically, or by combination of automatic and manual operations.

These and other objects and novel features of my invention will be more clearly and fully set forth in the following specification and claims.

In the drawings forming a part of my specification:

Figure 1 is a perspective view of a bacon package showing the general appearance thereof.

2

Figure 2 is a bottom plan view of the package shown in Figure 1.

Figure 3 is a diagrammatic view of the package blank showing the manner in which two similar blanks dovetail together.

Figure 4 is a top plan view of the blank with the transparent liner attached thereto.

Figure 5 is a view similar to Figure 4 showing the product in place and showing the package partially folded.

Figure 6 is a view similar to Figure 5 showing the next succeeding step in the folding operation.

Figure 7 is a view showing the next folding step after that shown in Figure 6.

The bacon package is best illustrated in Figures 1, 2, and 3 of the drawings and includes a back panel 10 of generally rectangular shape. This panel 10 is connected along a fold line 11 to a marginal flange 12. In use the panel 10 forms the back panel of the package while the panel 12 forms a flange extending along the lower edge of the package and covering the first strip of bacon or similar material.

The flange 12 is provided with a relatively narrow extension 13 which extends substantially flush with one edge 14 of the rectangular back panel 10. This extension 13 is designed to overlie one edge of each of the strips of bacon.

The extension 13 is foldably connected at 15 to a locking strip 16. The locking strip 16 is preferably provided with a rounded extremity 17 and a notch 19 which is designed to interlock with a slot 20 in the back panel 10.

As indicated in the drawings a shallow notch 21 is formed in the edge 22 of the blank which forms the upper edge of the backing panel. This notch 21 is designed to accommodate the locking tongue 16, which folds therein. As noted, the locking tongue is slightly narrower than the extension 13 so that the side edge 23 of the tongue is spaced inwardly from the edge 14 of the panel 10. As a result the notch 21 may be spaced from the corner of the panel 10 so that the locking tongue may be held from lateral movement with respect to the backing panel.

The blanks thus formed are attached to rectangular lining sheets 24 of cellophane or other suitable material. One edge of each lining sheet 24 extends substantially along the fold line 11 while the opposite edge thereof extends somewhat beyond the fold line 15. The end edges 25 and 26 project laterally beyond the edges 27 and 14 respectively of the panel 10. The lining sheet 24 is adhered to the flange 12 as well as to the extension 13. There is no adhesive connection between the lining sheet and the locking tab 16.

The various steps of packaging the bacon in the package are illustrated in the drawings. Figure 4 discloses the blank in readiness to receive the strips of bacon. These strips of bacon are usually arranged in edge overlapping relationship and form a rectangle in plan which extends substantially the area of the backing panel 10. However, in the packaging operation, the strips are placed over the adjoining portion of the package, the strips being placed upon the lining sheet 24 to overlie a rectangular area bounded by an extension of the edge 27, an extension of the fold line 15, the fold line 11, and the edge 14 of the extension 13. The bacon strips are shown in this position in Figure 5 of the drawings.

The strips of bacon are placed in proper position upon the lining sheet 24 when it is in the position shown in Figure 4 and the lining sheet is folded along a line of fold 29 which substantially coincides with the fold line 15. This arrangement forms a closure for the edges of the bacon strips and partially encloses the exposed surface of the bacon.

The liner 24 is next folded into the position shown in Figure 6 with the lateral edges 25 and 26 abutting or preferably overlapping to some extent. In other words, the liner is folded along the opposite edges 27 and 14 of the blank, these ends overlying the strips of bacon and enclosing the same. Thus in the position shown in Figure 6, the bacon is entirely enclosed within the wrapper.

The next step of the packaging operation is to fold the panel 10 over the bacon as indicated in Figure 7 of the drawings. When in this position the backing sheet 10 overlies the wrapped strips of bacon and acts to assist in supporting the same.

The locking tab 16 is next inserted through the slot 20 so that the notch 19 engages in this slot. The slot is preferably slightly off-set inwardly from the edge 14, beyond the edge 23 of the locking tab so that the tab is deformed slightly in inserting it through the slot. However, when the notch 19 engages an end of the slot 20 the lock is engaged and the extension 13 is securely attached to the backing panel 10. When the package is entirely wrapped, it has the appearance illustrated in Figure 1. The wrapped slices of bacon are visible throughout most of the area of the bacon, the end strip of the series being concealed by the flange 12 and one edge of each strip being concealed by the extension 13. The package is neat in appearance and may remain so in view of the fact that the body of the package is not permitted to come into contact with the strips of bacon. The package requires no overwrapping operation, thereby producing a neater and better appearing structure than would otherwise be readily obtained.

In the packaging of a product such as bacon, it is desirable that most of the air be excluded from the package during the wrapping operation. With a rectangular package of constant thickness, such a wrap is difficult to obtain as the strips are in overlapping relation and one edge of the last strip of the series projects beyond all of the other strips. It will be noted that as the flange 12 is connected to the backing 10 along a single line of fold, the package will conform to the gradual increase in thickness to the bacon strips and may be thinner along the end strips of the series in order to compensate for the difference in thickness at these points. Thus the package is effective in the preservation of the product.

In accordance with the patent statutes, I have described the principles of construction and operation of my bacon tray, and while I have endeavored to set forth the best embodiment thereof, I desire to have it understood that this is only illustrative thereof and that obvious changes may be made within the scope of the following claims without departing from the spirit of my invention.

I claim:

1. A package including a generally rectangular panel, a second panel integral with and foldably connected to

the first panel along a fold line coextensive with an edge, said second panel being substantially within the confines of said first panel when folded thereon and including a panel portion extending along the said fold line and an integral narrow right angularly extending portion at one end of the first named panel portion and extending in substantial alignment with an edge of said first panel at right angles to said fold line, said two panel portions leaving the major portion of said first panel exposed when folded thereupon, and an integral flap foldably connected to the end of said second panel portion of said second panel designed to fold over the edge of the first panel parallel to said fold line and to underlie said first panel, an integral transparent liner sheet of rectangular form overlying and adhered to said second panel along both portions thereof, said liner sheet extending substantially beyond the side edges of said second panel, and extending over at least a portion of said flap, but being free of attachment therewith.

2. A package constructed to display a relatively thin body of material; the package including a base panel of generally rectangular shape and of slightly greater dimensions than the thin body of material, a generally rectangular strip hingedly connected to an edge of said base panel and folded to overlie an edge of the thin body of material, a right angularly arranged generally rectangular strip integral with one end of said first named strip and extending over an end of the thin body of material, one edge of said right angularly arranged strip overlying and substantially coinciding with an edge of said base panel; said strips leaving exposed a generally rectangular area of said thin body of material, and an extension on said right angularly arranged strip foldably connected to an end thereof and foldable beneath said base panel, and interlocking means on said extension and said base panel, a transparent liner sheet of generally rectangular form secured to said strips and overlying the thin body of material, the liner sheet having an edge and folded opposite ends tucked between said base sheet and said thin body of material to completely enclose said thin body of material.
